(57) CLAIM

The ornamental design for a chaise as shown and described.

DESCRIPTION

FIG. 1 is a perspective view of a chaise according to our new design.

FIG. 2 is a front view of the chaise of FIG. 1.

FIG. 3 is a rear view of the chaise of FIG. 1.

FIG. 4 is a first side view of the chaise of FIG. 1.

FIG. 5 is a second side view of the chaise of FIG. 1.

FIG. 6 is a top view of the chaise of FIG. 1; and,

FIG. 7 is a bottom view of the chaise of FIG. 1.

The broken lines are included for the purpose of illustrating environmental and portions of the chaise which form no part of the claimed design.

1 Claim, 7 Drawing Sheets
